UNITED STATES PATENT OFFICE

2,571,056

VEGETABLE SEPARATOR

George J. Olney, Westerville, N. Y.

Application February 2, 1949, Serial No. 74,201

2 Claims. (Cl. 209—173)

1

My invention relates to a vegetable separator and I declare the following to be a full, clear, concise and exact description thereof sufficient to enable anyone skilled in the art to which it appertains to make and use the same, reference being had to the accompanying drawings in which like characters refer to like parts throughout.

The present invention is designed to improve over Patent 2,198,390 issued April 23, 1940, which was invented to separate both heavy and light foreign matter from green shelled peas, green shelled lima beans, all varieties of soaked dry beans and vegetables of like nature by means of a controlled circulating flow of water.

Although the operation under said patent was successful, under a certain load, when speeding it up, excessive water currents were produced during the separation of the heavy foreign matter such as gravel, bolts, nails, pieces of broken glass from the vegetable material. These excessive water currents caused waste of the peas, beans or other like vegetables.

The present invention is designed to increase the capacity or load of the machine over the prior device by feeding the material in such manner that both the heavy foreign matter and the lighter trash has more time and opportunity to separate from the good material.

This is done by dropping the heavy foreign matter separating unit well below the working surface of the flotation tank to give a greater separation area and the opportunity to deflect the upwardly flowing current through the throat of the machine by means of an adjustable curved top baffle plate, whereby to prevent its interference with the smooth flow across the top surface which carries light foreign material to a refuse receptacle.

Furthermore, the heavy foreign matter unit is separated, whereby the front section of the unit can be adjusted to give a variable opening to this part of the machine, and also allows for a quick removal of the other parts of the machine. The improvement allows also for the quick removal of the water deflecting plate located immediately in front of the feed hopper.

The material to be separated is fed into an accelerated deepening water medium which has no forward flow except what is induced by incoming material and the friction of the flow of water moving under the base of the feed hopper directly across the top deflecting plate which allows the light material or trash to be carried directly forward, while the good material and

2

heavy foreign matter slowly drop as they reach the accelerated depth of water. The heavy foreign matters will sink first separating itself from the good material which aided by an intermediate current moves forward and is carried there-beyond into a chamber of its own.

The above objects of the invention will be understood by referring to the drawings in which

Fig. 1 is a central vertical section of the machine.

Fig. 2 is a plan view of the machine.

Referring more particularly to the drawings the machine embodies an angle iron frame 1 supporting a feed hopper 2 at the left hand side 10 of the frame 1 above the water supply trough 3. An adjustable gate 5 is slidingly mounted on the right hand wall 6 of hopper 2.

Wall 6 of hopper 2 is substantially perpendicular, whereby the rear wall 7 slants towards wall 6. The hopper has two side walls 8, 8 that connect walls 6 and 7. It is open at both top and bottom. A cross frame angle iron 10 is welded to rear wall 7 near its bottom part to aid in supporting hopper 2. The ends of iron 10 are connected to frame 1.

The means for operating gate 5 relative to wall 6 of hopper 2 comprises rods 11, 11 located near to ends of gate 5 which extends across the machine. Rods 11, 11 slide in guide apertures made in lower angle iron 15 and upper bracket 16, 16 which are welded to wall 6 of hopper 2. The upper ends of said rods 11, 11 are threaded for the application of winged nuts 17, 17 mounted on the upper ends of rods 11, 11 extended above brackets 16, 16.

35 A smooth faced roller 20 is mounted on shaft 21 having loose bearings in upstanding bearing blocks 22, 22 attached to sides of the machine. It is located below but partially projecting into the whole length of lower opening 25 of hopper 2.

40 Roller 20 rotates clockwise and aids in carrying a given quantity of vegetables and accompanying foreign matter to the right below the lower end of adjustable gate 5, whereby to cause the vegetables and foreign matter to drop into the water in trough 3 at zone A located therebelow.

45 Trough 3 extends the width of the machine and one third the length of the machine. It comprises a lower slanting base 30 having a flange that is welded at 31 to the end and side walls of the machine. A water inlet pipe 32 having a plurality of apertures 23 therein extends across the machine. Apertures 23 are made in pipe 32 opposite baffle 35, whereby to direct the

flow of water thereagainst. Pipe 32 is projected through one of the side walls 33 of trough 3. The force of the water from pipe 32 is arrested somewhat by an L shaped partition 35 extending across the machine and welded at either end to the side walls 33, 33. The horizontal part 36 of partition 35 is spaced a short distance from slanting base 30, to allow the water to pass therethrough. It comes then in contact with dam 37 extending across the machine. Dam 37 has a flange 38 that is welded to base plate 30. The ends of said dam 37 are welded to side walls 33, 33 of trough 3. An adjustable U-shaped member 39 is fitted to dam 37. It has a frictional engagement therewith, whereby it can be held at any adjusted position to create an even flow over its top edge.

Beyond dam 37 trough 3 is divided into a plurality of compartments by upstanding thin partition plates 40 disposed longitudinally of trough 3, whereby to aid in preventing any cross currents on said base plate 30.

It has been found desirable to drop the heavy foreign matter separating unit well below the working surface of the flotation tank. To this end a removable plate 50 extending the width of the machine and disposed at an angle of about 40 degrees to base 39 is mounted near the end of base 30. It is held in place in a detachable manner at the upper end by a channel or lip member 51 that has its angled side 52 resting against side 53 of V-shaped member 54. Side 55 of member 54 is welded to the underside of base 30. The lower edge of right angle side 55 of channel member 51 rests on the upper surface of plate 50 when said plate 50 is in assembled position.

The lower end of plate 50 is bent at right angles at 57 with its free part terminating in a round trough 58. Part 58 rests against ledges 59, 59 riveted to the side walls 33, 33 of frame 1. Other ledges 60, 60 support plate 50 from beneath and are riveted to side walls 33, 33.

Swinging locking arms 61, 61 pivoted to walls 33, 33 at 62, 62 and provided with flanges 63, 63 at their lower free ends rest on plate 50 to hold the same in position.

In assembling plate 50 channel or lip 51 will be mounted to said plate 50 as shown in Fig. 1 and then lip 51 disposed in the opening provided by member 54, whereas the lower end of plate 50 will be disposed above ledges 60, 60 with its bent side or trough 58 resting against ledges 59, 59.

A passageway for the flow of water is made at 65 by the trough side 58 of plate 50 and the variable throat V-shaped member 66 held in adjusted position by headed bolts 67, 67 projecting through elongated slots 68 therein and through partition wall 69. Winged nuts 70, 70 are mounted on the threaded end of bolts 67, 67, whereby to clamp member 66 in place to wall 69.

Lip member 51 presents a vertical wall 56, whereby to provide a dead space in front for the discharge of water from the free end of plate 30.

Furthermore dropping the heavy foreign separating unit 72 hereinafter mentioned well below the working surface of the flotation trough 3 or water lever represented by the dotted line 73 will give opportunity to deflect the upwardly flowing current through the throat 65.

The means for deflecting the upwardly flowing current from throat 65 embodies an adjustable, curved top baffle plate 75 removably held in place by brackets 76, 76 attached to opposite sides 33, 33 of the machine and provided with open grooves 78, 78 with which the straight edges of plate 75 can slide and be held by frictional contact. The curved top of baffle plate 75 will prevent the upwardly flowing of current from throat 65 from interfering with the smooth slow flow of current across the top of separating tank 80, which slow current carries light foreign matter or trash. Adjustable V-shaped throat member 66 allows a variable opening for throat 65. Baffle plate 71 is welded at either end to side plates 33, 33 and projects up into grooves 78, 78 enlarged at their lower ends to permit plates 75 and 77 to overlap each other, to allow for adjustment.

There are disposed in vertical position in float tank 80 baffle plates 81, 82 and 83 spaced from each other and from the sloping side 85 of tank 80, whereby to aid in deflecting downward any peas that are floating just below the water level 73. Said baffle plates 81, 82 and 83 are graduated in height in the order named. Plate 81, however, has a curved upward lip 84 to further aid in diverting the peas downward, and a lower angled part 85 to aid in directing the flow of material towards passage 102. Said plates 81 to 83 inclusive extend across tank 80 and are welded at either end to walls 33, 33.

An adjustable gate 90 extends across the rear wall 91 of tank 80 and is held in place by headed bolts 92, 92 projecting through said side 91 and through elongated slots in gate 90. Gate 90 will divert downward any peas escaping past baffle plates 81, 82 and 83.

The upper part of rear wall 91 of tank 80 is bent downward at an angle to itself to form with walls 33, 33 a discharge outlet 95 for the light foreign matter into the inclined trough 96 supported at one end by wall 33 of the machine and also by the frame 1.

A pocket or receptacle 100 is formed by extending the four sloping sides of tank 80 thereto in an inverted pyramidal manner towards which peas or other vegetables gravitate and eventually settle. An upwardly slanting pipe 102 forming passageway between receptacle 100 and screen 106 is made by bending the material comprising one of the walls 91 of tank 80. Its open end 105 is extended into the end of the rotatable conical screen 106 mounted on rotatable shaft 107 extending through the center thereof. Shaft 107 is supported in bearings 108, 108 mounted on the frame 1 of the machine. It has a bearing in hub 110 of spider 111 forming part of the screen 106 and is held to turn therewith by set bolt 112 and woodruff key 113.

A stationary perforated pipe 114 is disposed centrally of receptacle 100. It has a bearing at one end in hub 110 provided with a bushing 115 and at the other has a bearing 116 in frame 1. It runs intermediately through a hub 117 provided with a bushing 118 of spider 111. Pipe 114 is connected to pipe 118 by an elbow 119. Pipe 118 has a shut off valve 120 therein. It runs to a source of water supply.

An ejector water pipe 125 is threaded to enlarged part 126 formed integral with wall 127 of receptacle 100. It is held therein by nut 128 threaded to said pipe 125. Ejector pipe 125 is connected to water pump 130 which in turn is connected to some source of water by a pipe 131 to force water directly across receptacle 100, whereby to force the vegetables up through pipe 102 into rotatable conical screen 106.

A water inlet pipe 135 is connected to the lower end of heavy foreign separating unit 72. There

is also a water supply pipe 136 attached at 137 to the water supply compartment 138. A plurality of openings 140 is made in the top of compartment 138 across the front thereof for the passage of the water to compartment 141 located above compartment 138. Compartment 141 is divided into six separate zones by partition plates 142 into each of which water flows through one of the openings 140. Furthermore, each of the six separate zones formed by plates 142 is divided into auxiliary zones by partitions 145 that extend in front of openings 140 to end of compartment 141. Pump 130 forces the water through the system of pipes.

Operation

Pump 130 is started to circulate the water through the various compartments and out through opening 32 into trough 3. Its passage will be checked somewhat by an L-shaped partition 35 and afterwards by dam 37 which previously has been adjusted to a predetermined height, whereby to allow an even passage of a limited amount of water of shallow depth to flow along trough 3. Beyond dam 37 the water will flow through the compartments formed by up-standing partition plates 40.

When the water reaches the end of slightly slanting plate 30 it will come in contact with lip member 51 and will drop abruptly perpendicularly from the free edge thereof and parallel to side 56 of lip member 51, whereby to prevent any eddies in front of said member 51.

After the water has started to flow through the machine the material including peas and foreign matter is dumped into the upper end of hopper 2, and comes in contact with roller 20 that has been set in motion previously to turn clockwise by an electric motor, not shown.

Roller 20 will feed the material out through the passage 3 between its surface and adjustable gate 5, and be assisted therein by the lubricating action of the shallow force of the running water down the inclined plate 30 through the channels formed by plates 40. When the material reaches the edge of lip member 51 the heavy foreign matter such as stones, sticks, glass, etc., will drop down abruptly on the steeply inclined removable plate 50, pass through throat 65 and lodge in heavy foreign separating unit 72 from where it can be expelled by ejector pipe 125.

The peas and light trash will be carried along on the surface of the slowly flowing current across the top of the chamber, whereby to carry the peas to the main separating tank 80 and the light trash therebeyond to discharge outlet 95 and inclined trough 96.

Dropping the stone separating unit 72 well below the water surface 73 of the flotation tank 80 will give opportunity to the deflected upward current through throat 65 to carry the good material forward, whereas the adjustable curved top baffle plate 81 will prevent its interference with the smooth slow flow necessary of the current across the top of tank 80 in order to handle properly the light trash.

Furthermore, separating the heavy foreign matter unit 72 from tank 80 and placing an adjustable V-shaped throat member 66 in connection therewith will allow for a variable opening at this location which is found desirable to accommodate a variance of currents that might effect the slow flow of the top current. Moreover, the plates 50 and 75 allow for a quick removal of the parts from each other for cleaning or repairing.

The feeding material as it reaches the edge of member 51 will allow the peas to slowly flow downward with the heavy or trash material dropping easily through said peas to the surface of plate 50.

Moreover the slow flow of water coming from underneath the feed hopper 2 and straight across deflecting plate 51 tends to spread the incoming material for a short distance in front of the hopper 2 and thereby accentuate both the separation of heavy and light material.

This same flow is in a direction towards the discharge end 95 of tank 80 and effects a slowly moving current which carries the light materials with it and outwardly over discharge end 95 of tank 80 to waste trough 96.

The deflector plate 51 will prevent any whirlpool action immediately in front thereof to prevent the trapping of light materials at this location, otherwise said light materials would become quickly waterlogged and sink with the good material or peas.

In separating materials like peas, some varieties have a specific gravity so close to that of the separating medium that a very close control of the working flow must be made. Separate induced means for forcing the good material out from the main flotation tank 80 after all separations have been made, relieves the current flowing through the stone separating throat 65 from this double duty and allows a much closer adjustment to be made at this point, giving naturally a better separation of heavy and light materials. Due to this result the uncontrolled currents do not impair the separation of light materials as there is a much smaller amount of water in circulation.

The former patent also showed slight upward currents between the three baffle plates at the front, towards feed hopper 2, due to the fact that the passage of water through the stone throat outlet 65 flowing upwardly at an angle acted like an injector that passed over the tops of the first two plates 81 and 82, which was just enough to carry some good peas up and out with the trash.

By dropping and deflecting this stone throat 65 current downwardly will allow this current to assist the flow of good material still further on its travel towards the discharge outlet 95 at the bottom instead of impeding this travel.

The force of the passage of water through throat 65 is gauged to move the light trash and good material upward but allows heavy material to sink.

The peas accumulated in pocket 100 of the main tank 80 will be forced up passageway 102 aided by the flow of water from ejector pipe 125 into conical screen 106 where they are washed by sprays of water from perforated pipe 114.

The peas in screen 106 can be removed for canning at the will of the operator. To this end screen 106 is made conical. Its rotation carries the material forward to aid in its discharge.

Shaft 107 is rotated by motor 150 connected thereto by sprockets and sprocket chain 151.

Having thus described my invention, what I claim as new and desire to secure by Letters Patent is as follows:

1. In a vegetable cleaner and separator, a trough having a slanting base, a dam mounted in said trough, a removable U-shaped member fitted to said dam, a removable plate disposed at an angle to said trough, a lip member having a vertical side to aid in holding said plate in position, ledges mounted in said separator for sup-

porting said plate, swinging arms mounted in said separator to aid in holding said plate in position, a trough formed on the lower part of said plate to aid in forming a passageway, a removable V-shaped member cooperating with said last named trough to complete said passageway, a separating unit formed below said passageway, a main tank formed in said casing, another tank disposed adjacent said first named tank for separating the good material from the foreign material; a baffle plate having a curved upper end for deflecting the flow from said passageway, other baffle plates mounted in said last named tank for deflecting the good material towards the bottom of said tank, a gate mounted to said tank for deflecting the good material into said tank and an exit passageway for the material to move out of said tank.

2. In a vegetable cleaner and separator, a casing, a trough formed in said casing, a dam mounted in said trough, a U-shaped member mounted on said dam, a plate disposed at an angle to said trough, a lip member to aid in holding said plate in position, said lip member having a vertical side, whereby to prevent eddies, ledges mounted to said casing for supporting said plate, swinging arms for holding said plate on said ledges, a right angle extension formed on said plate to aid in forming a passageway, a

5.
